US0D1070223S

(12) **United States Design Patent** (10) **Patent No.:** **US D1,070,223 S**
(45) **Date of Patent:** **** Apr. 8, 2025**

(54) **PART OF CABIN FOR TELESCOPIC LIFTER**

(71) Applicant: **MANITOU ITALIA S.R.L.**,
Castelfranco Emilia (IT)

(72) Inventor: **Simone Bonaretti**, Scandiano (IT)

(73) Assignee: **MANITOU ITALIA S.R.L.**,
Castelfranco Emilia (IT)

(**) Term: **15 Years**

(21) Appl. No.: **29/791,099**

(22) Filed: **Dec. 29, 2021**

(51) LOC (15) Cl. **12-05**

(52) U.S. Cl.

USPC **D34/35; D15/30**

(58) **Field of Classification Search**

USPC D34/34, 35, 37; D15/23, 30; D12/96,

D12/404, 191

CPC ... B66F 9/0759; B66F 9/07545; B66F 17/003

See application file for complete search history.

(57) **CLAIM**

The ornamental design for a part of cabin for telescopic lifter, as shown and described.

DESCRIPTION

FIG. 1 is a top, left, back perspective view of a part of cabin for telescopic lifter, showing the new design;

FIG. 2 is a left side view thereof, the right side view being a mirror image thereof;

FIG. 3 is a top view thereof;

FIG. 4 is a bottom view thereof;

FIG. 5 is a front view thereof; and,

FIG. 6 is a back view thereof.

The broken lines showing a cabin in FIGS. 1-3 depict environment and form no part of the claimed design. All other broken lines depict portions of the part of cabin for telescopic lifter that form no part of the claimed design.

1 Claim, 3 Drawing Sheets
